UNITED STATES PATENT OFFICE

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK

METHOD AND APPARATUS FOR MAKING PRONGS FOR LOOSE-LEAF BINDERS

Application filed November 11, 1930. Serial No. 494,866.

This invention relates to the making of prongs or half-rings for loose-leaf binders of the ring type.

In the construction of such binders, it is common to make the binding elements, which enter the holes in the loose-leaves or sheets to be bound, as divided rings, the half-rings of which are riveted or otherwise fastened to plates which are mounted to have a rocking movement whereby to open or close the rings,—a spring-plate or other resilient means being provided for holding the parts in either the closed or open position. Examples of such constructions are illustrated 15 in my Patents Nos. 1,468,845, granted September 25, 1923, and 1,634,125, granted June 28, 1927. For convenience I will herein refer to the half-rings as "prongs". In the closed position these prongs fit together and form a complete closed ring.

In the manufacture of such ring binders, it is desirable to practice the utmost economy consistent with the production of a sufficiently strong product having proper exactitude in operation. The economic production of the prongs has presented a serious problem. They have heretofore been made, one at a time, by feeding forward the wire stock, cutting it off, and then bending to shape. This has been generally mainly a hand operation, although attempts have been made to perform it by automatic machinery.

According to the present invention, the wire stock is fed forward and cut off at a length adequate for making two prongs. The wire is then bent to approximately the shape of two prongs united by a middle portion; then the middle portion uniting them is severed to separate the two prongs; and these are pinched between dies to give them a set in their final shape. Thus two prongs (which may be regarded as the two halves of one complete ring) are struck out at one operation, which not only doubles the product, but has certain other advantages which will be hereinafter stated.

The operation is performed by means of a pair of dies and their accessories, a suitable construction of which is shown in the accompanying drawings,—wherein—

Figure 1 is an elevation of the dies, the lower die being partly in section in a plane parallel with the line of feed of the stock;

Fig. 2 is a fragmentary transverse section on the line 2—2 in Fig. 1;

Fig. 3 is a plan of the cutting-off die which initially severs the stock;

Fig. 4 is a transverse section of the binding elements of a suitable form of ring binder, including the prongs and their carrier-plates and spring-plate, which illustrates the mode of mounting the prongs upon the carrier-plates by riveting;

Fig. 5 is a plan of the ring binder elements shown in Fig. 4;

Fig. 6 shows the two prongs as first bent and before cutting them apart;

Fig. 7 shows one of the prongs after severance, being the completed product of the present invention.

The method will be best understood after the apparatus has been described.

Referring to Fig. 1, A is an upper die and B a lower die, which are mounted in any suitable manner to be moved toward one another to operate on the stock and to be separated to release the stock. Normally the lower die B would be mounted on the table of a power-press, and the upper die A carried by the movable platen or slide of such press. The lower die is provided with a guide *a* for the wire or stock X from which the prongs are to be formed. This stock is fed through longitudinally in the path of the dotted lines *b* and is arrested by a stop *c*. The feed may be manual, although any usual automatic feed may be provided if desired. The wire stock will, of course, be previously straightened in any well-known manner, and a guide *d* may be provided adjacent the stop *c* to hold the free advancing end of the wire straight while it is being acted upon by the dies. The lower die is formed with two arc-shaped recesses *e*, *e*, between which is a separating portion *g*, which is preferably flat and level, as shown. The upper die is formed with two rounded projections *f*, *f*, between which is a portion *h* corresponding generally to the portion *g* of the lower die. A cutter C is provided for severing the wire after the required length

has been fed into place. This is conveniently carried by the upper die, and as it descends it enters a corresponding recess C' in the lower die, the two parts acting as a shear for cutting off the wire. The cutter may merely 5 cut the wire, or it may cut out a short piece of scrap, as desired. This cutter gives any desired formation for the abutting ends of the prongs when assembled in place.

In operation the wire, after having been 10 fed into place against the stop c, is, by the descent of the upper die, first severed by the cutter C and then acted upon by the rounded projections or bosses f, f and carried down into the recesses of the lower die. It is thus 15 bent to form the shape shown in Fig. 6, in which the blank includes two attached prongs which have received approximately their final form. By a further operation the blank 20 shown in Fig. 6 is severed at the middle, by means of a cutter or die D of any suitable construction and which may or may not be carried by the upper die A. The severing of the blank shown in Fig. 6 may be performed 25 by a separate operation, but it is most convenient and expeditious to accomplish this by the same stroke of the press. For this purpose the cutter D is conveniently carried by the upper die A, being a projection from the 30 intermediate portion h thereof and which, toward the end of the stroke of the upper die, cuts through the middle portion of the double blank, for which purpose it may enter a recess D' in the middle portion g of the lower die, the parts D and D' thus co-operating as 35 a shear to cut out a small piece of scrap which drops down through a clearance opening i in the lower die. Similarly the scrap produced by the shearing action of the cutter C 40 and socket C' also drops down through a clearance opening j.

As the two dies finally come together, they 45 give the now-severed blanks a final pinch which imparts to them their precise contour. In so doing it is desirable that at k the stock 50 be bent to a fairly sharp corner, as this is the portion which eventually will rest upon the surface of the prong carrier-plate when the prong is riveted to the plate. This is shown 55 in Fig. 4, where the shank m of the prong is passed through the plate and its end swaged down to form a rivet head beneath. In Fig. 4 the prongs are designated E, E, and their carrier-plates F, F. These plates are shown 60 as having a direct rocking engagement at their inner edges and being forced toward each other by a spring-plate G, which is of usual construction.

Thus it will be seen that the method comprises the cutting from the stock of a suitable length of wire, the bending of this into a double blank of yoke form, as shown in Fig. 6, and then cutting this in two at the middle to form two complete prongs, as shown in 65 Fig. 7. The blank (Fig. 6) might be given

the exact curvature of final contour of the two prongs before it is severed; but, for convenience in accomplishing the entire method at one stroke of the press, it is desirable to perform the severing just preceding the final 70 pinch which gives the prongs their set shape.

The wire stock is usually flattened or of approximately elliptical cross-section, and the dies may be grooved to receive such stock, as is apparent from the cross-section, Fig. 2. 75

It is customary to make the mating ends of the prongs with interfitting notches so that, when closed together, they shall interfit, as shown in Fig. 5. This notching is accomplished by the cutter C in association with the 80 lower die C', each having the contour shown in the plan view, Fig. 3. Thus the one cutter serves for thus notching the ends of both prongs so that, when mounted on their plates and assembled, the prongs may fit properly 85 together.

It is desirable that the dies be so proportioned that the projections or bosses f, f shall come into contact with the wire blank immediately upon its severance by the cutters C, C'. It results that the cut-off portion of the blank is at no time free or unsupported. The instant it is severed, it receives the pressure of the bosses f, f above, while still held at its ends on the shoulders 90 p, q of the lower die. A slight further movement of the upper die bends the middle portion of the blank down upon the middle recess g of the lower die; this amounts to clamping the middle portion of the blank 100 (due to its stiffness) between the two dies, so that the continued movement of the upper die bends the blank to both sides of its middle to quite the same effect as if the middle were clamped fast between upper and 105 lower members. It results from this that the bending of the blank draws both of its end portions toward the middle so that, when finally shaped, it occupies the position in the lower die shown in Fig. 1. This is true irrespective of the action of the middle cutter D which, if rigidly carried by the upper die, further holds the middle portion of the blank 110 from the instant when it begins to penetrate it. After the upper die has ascended to a 115 suitable height, the severed blank,—now constituting two prongs,—is removed from the lower die, for which purpose any usual known ejector may be provided.

The invention is applicable for the production of prongs or binder elements of other shapes than the half-rings shown. The invention may be modified in any way within the skill or judgment of mechanics or constructors according to any existing requirements. 120

I claim as my invention:

1. A method of making prongs for binders consisting in cutting off a length of wire suitable for two prongs, then bending the 125

wire on both sides of its middle portion to form the curved portions of the prongs, and finally severing the middle portion whereby two separate prongs are simultaneously formed.

2. A method of making prongs for binders consisting in feeding a wire stock past a cutter for a length sufficient to form two prongs, severing the stock by said cutter gripping the blank on opposite sides, and then bending the severed blank on both sides of its middle portion to form the curved portions of two prongs, and finally severing the blank at its middle whereby two separate prongs are simultaneously formed.

3. A method of making prongs for binders consisting in cutting off a length of wire suitable for two prongs, engaging the blank between opposite dies whereby it is clamped fast at its middle portion, then bending the severed blank at both sides of the clamped middle portion to form the curved portions of the prongs, and finally severing the blank at its middle whereby two separate prongs are simultaneously formed.

4. An apparatus for making prongs for binders comprising upper and lower dies adapted to grip between them and bend a length of wire corresponding to two prongs, the dies having coinciding straight middle portions and symmetrically curved reciprocal portions on opposite sides thereof adapted as they come together to bend the blank into the curved form of two prongs, and a cutter at the middle portions of the dies for severing the blank into two separate prongs.

5. The apparatus of claim 4 with a cutter for cutting off the wire to leave a blank of suitable length in position for bending between the dies.

6. An apparatus according to claim 4 having a stop for limiting the feed of the wire stock on one side of the dies and a cutter on the other side of the dies for severing the stock, whereby to leave between them a length of wire suitable for forming two prongs.

7. An apparatus for making prongs for binders, comprising means for feeding the wire stock for a length sufficient to form two prongs, a cutter for severing the stock, dies for gripping the blank on opposite sides adapted to bend the severed blank on both sides of its middle portion to form the curved portions of two prongs, and means for finally severing the blank at its middle whereby the two prongs are separated.

8. An apparatus for making prongs for binders, comprising means for feeding and cutting off a length of wire suitable for two prongs, opposite dies engaging the wire between them, whereby the blank is clamped fast at its middle portion, means for bending the severed blank at both sides of the clamped middle portion to form the curved portions of the prongs and means for finally

severing the blank at its middle, whereby two separate prongs are simultaneously formed.

In witness whereof, I have hereunto signed my name.

CLARENCE D. TRUSSELL.
